(57) CLAIM

I claim the ornamental design for tassel, as shown and described.

DESCRIPTION

FIG. 1 is a front view;

FIG. 2 is a rear view thereof;

FIG. 3 is a left side view thereof;

FIG. 4 is a right side view thereof;

FIG. 5 is a top view thereof; and,

FIG. 6 is a bottom view depicted by broken lines inasmuch as no claim is made to any component of the bottom view.

The broken away symbols in the drawings indicate the appearance of any portion of the article between the break lines forms no part of the claimed design.
